CLAIM

We claim the ornamental design for a contoured seating assembly, as shown and described.

DESCRIPTION

FIG. 1 is a top perspective view of a contoured seating assembly of the present invention;
 FIG. 2 is a top plan view thereof;
 FIG. 3 is a rear elevation view thereof;
 FIG. 4 is a left side elevation view thereof;
 FIG. 5 is a front elevation view thereof; and,
 FIG. 6 is a right side elevation view thereof.

1 Claim, 4 Drawing Sheets See application file for complete search history.
